Des. 247

John F. Rathbone. Albany, New York.
Letters Patent No 244. Dated Oct 23rd 1849.
The Schedule referred to in this Letters Patent and making
part of the same.

To all whom it may concern: Be it known that I, John F. Rathbone of the City of Albany, and State of New York, have produced a new ornamental design for an Air Tight Cooking Stove, which I call the "Republican Air tight Stove", and I do hereby declare that the accompanying and annexed drawing is a full and accurate delineation of a Stove constructed after my design; the side not represented in the drawing being similar to and symmetrical with that represented.

What I claim as my production and desire to secure by Letters Patent is the combination and arrangement of ornamental figures and forms as represented in the accompanying drawing, making an ornamental design for an Air tight Cooking Stove.
